(57) **CLAIM**

The ornamental design for an electrical connector as shown and described.

DESCRIPTION

FIG. 1 is rear, top and right perspective view of an electrical connector according to our new design.

FIG. 2 is a front, bottom, right perspective view thereof;

FIG. 3 is a rear, bottom, left perspective view thereof;

FIG. 4 is a front, top, left perspective view thereof;

FIG. 5 is a rear, top, right perspective view thereof;

FIG. 6 is a rear, bottom, left perspective view thereof;

FIG. 7 is a front, bottom, right perspective view thereof;

FIG. 8 is a front, top, left perspective view thereof;

FIG. 9 is a rear elevation view thereof;

FIG. 10 is a front elevation view thereof;

FIG. 11 is a top plan view thereof;

FIG. 12 is a bottom plan view thereof;

FIG. 13 is a right side elevation view thereof; and,

FIG. 14 is a left side elevation view thereof.

The evenly spaced dashed lines depict the portions of the electrical connector that form no part of the claimed design. The dot-dash broken lines define the bounds of the claimed design and form no part thereof.

1 Claim, 12 Drawing Sheets
